US0D1052053S

(12) **United States Design Patent** (10) Patent No.: **US D1,052,053 S**
(45) Date of Patent: ** Nov. 19, 2024

(54) **MALE FERRULE**

(71) Applicant: **Jameson, LLC**, Clover, SC (US)

(72) Inventors: **Carlos Becerra Alvarado**, Charlotte, NC (US); **Timothy Beed**, Lake Wylie, SC (US)

(73) Assignee: **Jameson, LLC**, Clover, SC (US)

(**) Term: **15 Years**

(21) Appl. No.: **35/519,368**

(22) Filed: **Nov. 29, 2023**

(80) **Hague Agreement Data**

Int. Filing Date: **Nov. 29, 2023**

Int. Reg. No.: **DM/233628**

Int. Reg. Date: **Nov. 29, 2023**

Int. Reg. Pub. Date: **Dec. 15, 2023**

(51) **LOC (14) Cl.** **23-07**

(52) **U.S. Cl.**

USPC **D23/259**; D23/213

(58) **Field of Classification Search**
